(57) **CLAIM**

The ornamental seat design, as shown and described.

DESCRIPTION

FIG. 1 is a front perspective view, showing my ornamental design of a seat with a seat cover;

FIG. 2 is a rear perspective view without the seat cover;

FIG. 3 is a rear view without the seat cover;

FIG. 4 is a left side view without the seat cover; the right side view is a mirror image thereof;

FIG. 5 is a front perspective view with the cover shown apart from the seat;

FIG. 6 is a rear perspective view with the cover shown apart from the seat;

FIG. 7 is a front perspective view with the cover removed from the seat and with the seat partially folded; the bottom is substantially unornamented;

FIG. 8 is a rear perspective view with the cover removed from the seat and with the seat partially folded;

FIG. 9 is a top view of the back rest with the cover removed from the seat;

FIG. 10 is a perspective front view of the back rest with the cover removed from the seat;

FIG. 11 is a front view of the back rest with the cover removed from the seat;

FIG. 12 is a right side view of the back rest with the cover removed from the seat; the left side view is a mirror image thereof;

FIG. 13 is a perspective front view of the bottom rest with the cover removed from the seat;

FIG. 14 is a top view of the bottom rest with the cover removed from the seat;

FIG. 15 is a front view of the bottom rest with the cover removed from the seat; and,

FIG. 16 is a right side view of the bottom rest with the cover removed from the seat; the left side view is a mirror image thereof.

1 Claim, 7 Drawing Sheets
